UNITED STATES PATENT OFFICE.

ARLINGTON MOORE, OF NEW YORK, N. Y., ASSIGNOR, BY MESNE ASSIGNMENTS, TO MAXMOOR CORPORATION, OF NEW YORK, N. Y., A CORPORATION OF DELAWARE.

ANTIDETONATION PISTON-HEAD FORMATION FOR INTERNAL-COMBUSTION ENGINES.

Application filed January 17, 1927. Serial No. 161,524.

My invention relates to four-cycle internal combustion engines consuming volatile liquid fuel, and particularly to the formation of an anti-detonation piston head for such engines.

- An object of the present invention is the provision of a piston for such engines having a head with stepped surfaces, comprising alternate steps and risers, and in which 10 the riser surfaces are divided into parts having abrupt angular relation to each other, whereby pressure waves accompanying combustion are broken up, not merely by coming into contact with the tread surfaces of 15 the stepped piston head arranged at varying levels, but the riser surfaces are also adapted to do their part of the work of breaking up the pressure waves and avoiding detonation. 20 Another object of the invention is the combination in one structure of step formations of separate types, and in particular the combination in a single structure of circular and substantially square steps, the combination 25 of a plurality of step formations being deemed superior to use of a single form of step formation throughout.

In the accompanying drawings illustrating an embodiment of the invention, Fig. 1 30 is a plan view and Fig. 2 a part side and part vertical sectional view of a piston of a four-cycle internal combustion engine consuming volatile liquid fuel and embodying my invention.

The piston is designated by reference character 10. Its head is of stepped formation. The lowest or outer step, comprising 35 the tread surface 12 is of circular outline, as is also the next higher step comprising the tread surface 14 and riser surface 16. While several of the circular step members 40 may be used, the showing made in the drawings is sufficient for purposes of illustration.

The circular tread portions 12 and 14 are 45 surmounted by a series of tread portions 18, 20 and 22, which are angular and preferably substantially square in outline, the riser surfaces 24, 26 and 28 being preferably divided into four parts, as 24^a, 24^b, 24^c, 24^d, making 50 abrupt and, as shown, approximately right angles with one another, though the corners are preferably rounded off somewhat as indicated at 30, to avoid any tendency to excess localized heating and consequent pre- 55 ignition.

The combination of differently shaped steps and the varying nature of the riser and tread surfaces presented is well adapted for producing agitation of the charge and residual gases of the prior cycle during intake stroke and during the compression stroke, and upon ignition near the end of the compression stroke of the charge material in its state of agitation, the flame propagation is accelerated. By the contact of pressure waves during combustion with the variously formed head and riser surfaces the charge gases cannot be divided into stagnated pockets and brought up to a temperature and pressure producing the self-ignition explosive effect known as detonation. 60

Furthermore, the stepped piston head of highly extensive surface area, as compared with the usual plain form of piston head, is of great utility in obtaining the complete 75 gasification of any wet mixtures supplied to the engine cylinders by storing up heat during combustion and delivering this heat to the incoming charge material of the subsequent cycle, whereby the piston head surfaces are cooled and the heat is taken up by the charge, largely as latent heat of vaporization, thus promoting combustion without substantial loss of volumetric efficiency. 80

The subject matter of my invention disclosed in this application and not claimed 85 therein is disclosed and claimed in part in my application Serial No. 125,414, filed July 28, 1926, and in part in my application Serial No. 141,289, filed October 13, 1926. 90

I claim:

1. A device for reducing detonating effects in the combustion chamber of internal combustion engines comprising a step formation presenting relatively abrupt angles between the tread and riser portions thereof and between different parts of the riser portion thereof. 95
2. A device for reducing detonating effects in the combustion chamber of internal combustion engines comprising a step formation having the superimposed steps thereof substantially polygonal in cross-section. 100
3. A device for reducing detonating effects in the combustion chamber of internal combustion engines comprising a step formation substantially square in cross-section. 105
4. A piston for four-cycle internal combustion engines consuming volatile liquid fuel, having a stepped head, comprising a 110

step of circular formation surmounted by a step of angular formation.

5. A piston for four-cycle internal combustion engines consuming volatile liquid fuel, having a stepped head, comprising a step of circular formation surmounted by a step of square formation.

6. A piston for four-cycle internal combustion engines consuming volatile liquid fuel, having a stepped head comprising a series of steps of circular formation surmounted by a series of superimposed steps of angular formation.

7. A piston for four-cycle internal com-

bustion engines consuming volatile liquid fuel, having a stepped head comprising a series of steps of circular formation surmounted by a series of superimposed steps of square formation.

8. A piston for four-cycle internal combustion engines consuming volatile liquid fuel, having a stepped head comprising superimposed steps having the riser portions thereof divided into parts with relatively abrupt angles between said parts.

In testimony whereof, I have signed my name hereto.

ARLINGTON MOORE.
